UNITED STATES PATENT OFFICE.

EGBERT H. GOLD, OF SHELBY, INDIANA.

AUTOMATIC HEATING SYSTEM.

1,219,546.

Specification of Letters Patent. Patented Mar. 20, 1917.

Application filed December 14, 1908. Serial No. 185,122.

To all whom it may concern:

Be it known that I, EGBERT H. GOLD, a citizen of the United States, residing at Shelby, in the county of Lake and State of Indiana, have invented certain new and useful Improvements in Automatic Heating Systems, of which the following is a specification.

My invention relates to a heating system, 10 in which the admission of the heating medium to the radiating system is controlled by a device located within or connected with the radiating system.

More specifically, my device is particularly adapted for use in connection with train heating systems in which a high pressure train pipe is combined with low pressure radiating pipes, the admission of steam from the train-pipe to the radiating pipes 20 being preferably controlled by a device which is exposed outside of the apartment to be heated.

One object of my invention is to provide simple and effective means, located within 25 a compartment connected with the radiating system, for automatically controlling the supply of steam to the radiating system.

The above object and such others as may hereafter appear are attained by the devices 30 shown in the accompanying drawings, in which—

Figure 1 is a perspective view of one embodiment of my invention.

Fig. 2 is a sectional plan view on the line 35 2—2 of Fig. 3.

Fig. 3 is a vertical sectional view of my automatic control apparatus.

Fig. 4 is a detail on the line 4—4 of Fig. 5; and

Fig. 5 is a detail on the line 5—5 of Fig. 3.

Like reference characters indicate the same parts in the several figures of the drawings.

Referring by figure to the accompanying drawings, 1 indicates a train-pipe, 2 a feed-pipe extending from the train-pipe to the valve casing 3, 4 is a hand operated supply valve, 5 indicates the floor of the car, 6 is a feed-pipe leading from the valve casing 3 to the radiating pipes 7, 8 is the return or drip pipe leading to the valve casing 3, 9 is the discharge pipe and 10 is the casing of the diaphragm chamber, said casing being preferably provided with ventilation openings 55 such as 11. The valve casing 3 is provided with an inlet chamber A, a valve chamber B

and an outlet chamber C. The chambers A and B are separated from the chamber C. The supply pipe 2 connects through a suitable port with the inlet chamber A. The 60 web D constituting the top of the inlet chamber A is provided with a valve seat E. Fitted to this valve seat E is a valve F provided with a stem G and also provided with a polygonal collar, or washer, H. Screwed 65 into the top of the valve chamber B is a cap I provided on its under face with a suitable seat for engaging the washer or collar H. Mounted upon the valve stem G between the washer H and cap I is a washer of packing 70 material J. As shown in the drawings, the valve stem is also provided with a stuffing-box K, but this stuffing-box is not considered essential where the packing washer J is used.

Mounted upon the cap I and surrounding 75 the stem G is a helical spring L, upon which rests a cap M provided on its under side with a suitable seat for the spring L. The cap M is also provided with an upwardly projecting stem m upon the upper end of 80 which is screwed a nut N, which is then riveted in place by upsetting the end of the stem m. The valve casing 3 is provided, adjacent to its upper edges, with inwardly projecting bosses 84. Mounted within these 85 bosses and extending across the space between them is a pivot-bolt O. Pivoted mounted upon the bolt O is a lever P which is forked at opposite ends, one of the forked ends engaging the stem m upon the cap M. 90

Extending longitudinally of the discharge pipe 9 is a stem Q which projects upwardly through the chamber C and is pivoted to the lever P (vide Fig. 5). The lower end of the stem Q rests upon a 95 familiar form of diaphragm R which is mounted within the diaphragm casing 10 in a familiar manner.

The drip-pipe 8 discharges into the chamber C and the chamber C discharges into the pipe 9, as clearly shown in Fig. 3.

In the preferred form of my device the parts are mounted as shown, viz., with the diaphragm chamber projecting below the floor of the car and in an exposed position 105 and with the valve casing preferably mounted above the floor of the car, although neither of these points is essential.

With the apparatus as so constructed, the operation of my device will be as follows:

If the device is applied to a car, the pressure in the train pipe may be as high as

sixty pounds or higher. Upon opening the supply valve 4 this high pressure steam will rush through the pipe 2 into the chamber A, then through the valve into the valve 5 chamber B and then through the pipe 6 into the radiating pipes of the car.

It will be seen that the pressure of the steam will tend to force the valve upwardly and the collar H will carry the packing ring 10 or washer J with it until the washer is securely seated against the under side of the cap I, so that the steam pressure will hold the packing ring tightly in position and will make a tight joint at this point.

15 The cold air will be forced through the radiating pipes, out through the drip-pipe 8, into the chamber C and thence through the discharge pipe 9, through the diaphragm chamber 10 and out at the bottom of the diaphragm chamber. As soon as the steam fills the radiating pipes to such a degree that the vapor escaping through the diaphragm chamber 10 is of sufficiently high temperature to expand the diaphragm R, the expansion of the diaphragm R will lift the stem Q and by means of the lever P and stem G will close the valve F, thereby shutting off the steam supply.

This, theoretically, will be the operation 30 of the apparatus. As a matter of practical experience it has been found that as soon as the temperature within the diaphragm chamber begins to rise, the diaphragm will start to expand and will begin to close the 35 inlet valve. In view of the fact that a constant condensation is going on within the radiating system and connecting pipes, the partial closing of the inlet valve will tend to lessen the temperature within the radiating pipes and their connections and consequently the point will soon be reached where the amount of steam admitted through the inlet valve will be sufficient to keep the temperature in the diaphragm chamber at a 40 point where the diaphragm will expand just enough to hold the inlet valve at that point.

As previously noted, when the thermostat R is wholly or partially contracted, the pressure of inflowing steam against the valve F 50 tends to force the valve open. It will also be noted that the weight of the stem Q and connected parts will operate the lever P to open the valve when the thermostat R is contracted, and the expansion of the spring 55 L, while also tending to move the parts in a direction to open the valve, is mainly useful to hold the lower end of the stem Q in constant contact with the thermostat and to serve as an anti-rattler when the thermostat 60 is contracted. In the embodiment of my invention shown in the drawings, the weight of the stem Q is sufficient to at all times open the valve by the actual gravity when the thermostat is contracted, regardless of 65 whether or not steam is being supplied to

the system. The spring L serves, incidentally, as an additional positive valve opening device, and when the system is being supplied with steam, the pressure of the inflowing steam will be effective to open the valve 70 independent of the spring L and the stem Q.

Among the advantages by way of simplicity, economy in installation and in maintenance, safety and effectiveness, which are incident to the above-described car heating 75 system, I note the following:

First. The system is easily applied to a car without cutting sills or floor joists.

Second. By using steam at low pressure within the radiating system, it is not necessary 80 for the radiators, return bends and fittings to withstand the high train-pipe pressure, as with the direct steam heating systems now in use, and, therefore, much lighter radiators and fittings may be used.

Third. There being no sudden filling of the radiating system with train-pipe steam at high pressure and high temperature, there is no sudden expansion of the fittings and consequent liability to damage and leakage.

Fourth. My system automatically distributes a substantially equal supply of steam to all cars in the train, since the high-pressure steam in the train-pipe, being checked in its flow into the radiating system of each 95 car, will promptly fill the train-pipe and will then flow evenly into all the cars on the train.

Fifth. My system automatically maintains an even temperature in all the radiators on the train at all times.

Sixth. The external exposure of the thermostat insures sensitive and quick action of the thermostat in a manner familiar in the art.

Seventh. Because of the even temperature maintained, the amount of radiating surface necessary to be installed in a car may be more accurately determined.

Eighth. All of the cars in the train will be 110 heated at substantially the same time, instead of successively, as with present systems.

Ninth. There are but two valves, to-wit, one feed valve for each side of the car, to be 115 installed and to be manually operated, as against four such valves in other systems.

Tenth. There are no drip-valves to be installed or to be manually operated, thereby eliminating the expense of installation, the 120 cost of maintenance and the element of uncertainty which is inherent in every device which must be operated by hand.

Eleventh. When the train is put out of service there are no valves to be operated to 125 insure the drainage of the pipes of the heating system, as the system is open and unobstructed from end to end and invariably automatically and quickly drains itself.

Twelfth. No possibility of freezing.

Thirteenth. No cost for maintenance.

Fourteenth. No over-heating of the cars; and

and
Fifteenth. An economical use of the steam,
5 thereby avoiding waste of steam and, inci-
-dental thereto, avoiding expense and light-
-ening the load upon the locomotive.

I claim:

1. The combination with a car, of a radiator therein, constantly open to the atmosphere, means for supplying steam thereto at a substantial pressure, an admission valve for said radiator arranged to be closed against supply pipe pressure, a thermostat at the discharge end of said radiator, operative connections between said thermostat and said valve comprising a rod adapted to be actuated by the expansion of said thermostat to close said valve and to be actuated

by gravity in a direction to open said valve 20 upon the contraction of said thermostat.

2. The combination with a car, of a radiator therein constantly open to the atmosphere, an admission valve for said radiator, a thermostat at the discharge end of said radiator, operative connections between said thermostat and said valve, said connections comprising a rod adapted to be actuated by the expansion of said thermostat to close said valve and to be actuated by gravity in a direction to open said valve upon the contraction of said thermostat, and means constantly tending to actuate said structure in a direction to open said valve. 25 30

ECBERT H. GOLD.
